UNITED STATES PATENT OFFICE.

THEODORE THORSON, OF SPOKANE, WASHINGTON.

ROPE-HOLDER.

1,368,667.

Specification of Letters Patent. Patented Feb. 15, 1921.

Application filed January 15, 1920. Serial No. 351,535.

To all whom it may concern:

Be it known that I, THEODORE THORSON, a subject of the King of Norway, residing at Spokane, in the county of Spokane and 5 State of Washington, have invented certain new and useful Improvements in Rope-Holders, of which the following is a specification.

My present invention relates to improvements in rope holders of the one piece type, 10 designed especially for use in stretching, tightening, and holding tent ropes for securing the tent to stakes, and particularly adapted for holding the ropes in straight 15 lines and taking up slack in the ropes. While I hereinafter describe the device as used in connection with tent ropes, it will of course be understood that the holder may with facility be adapted for use in other 20 ways for stretching and holding a rope or cord, but the simplicity and efficiency of the device commends it for use especially as herein stated.

The invention consists essentially in a one 25 piece holder, preferably formed of hard wood or the like and fashioned with openings therethrough for the retention of the knotted end of a rope and to form a bight or loop to be passed around an anchoring 30 stake, and by means of the specially constructed block or holder, the same may be used as a lever to draw and tighten the rope and hold it taut in connection with the 35 loop, stake, and the end attached to the tent, all as will be hereinafter more specifically referred to and pointed out in the appended claims.

In the accompanying drawings I have 40 illustrated one complete example of the embodiment of my invention in which the parts are combined and arranged according to the best mode I have so far devised for the practical application of the principles of my invention.

45 Figure 1 is an assembly view illustrating the application of the rope holder to a tent rope and showing the rope stretched between a portion of a tent and the anchoring stake.

50 Fig. 2 is an enlarged detail view of the rope and its holder, showing the operative position of the holder in full lines, and indicating in dotted lines the manner of draw-

ing the rope to take up slack for securing the rope taut between the tent and stake. 55

Fig. 3 is a longitudinal, central sectional view through the holder or wooden block.

In order to illustrate the use of the device I have shown or indicated at 1 a portion of a tent top, an anchoring stake 2, and the 60 rope 3 has one end 1^a attached to the tent in usual manner, while its other end is fashioned with a loop or bight 3' and passed around the stake 2 in customary mode.

The holder, indicated as a whole by the 65 numeral 4, is preferably of hard wood and of suitable or varied sizes, rectangular or oblong in shape, and at its upper side is provided with a neck or contracted opening 5 through which one end of the rope is passed 70 and knotted as at 6. To permit freedom of movement of the rope adjacent the neck, a conical recess or opening 7 is provided, which extends through the block perpendicular to its longitudinal axis, with its 75 larger or flaring opening at the under side of the block, opposite the smaller neck opening 5, for retaining the knot 6.

A second opening 8 is bored, obliquely through the block providing wide open ends 80 one of which is fashioned with an abrupt, semi-circular shoulder 9 at the outer side of the flared upper opening, and another, complementary shoulder 10 on the under face of the block is fashioned at the inner 85 side of the flared opening.

In the utilization of the block, one end of the rope is first passed through the flaring opening or recess 7 and the neck 5 and then 90 knotted as at 6, after having been threaded through the passage 8 to form the loop or bight 3', and the loop is ready for attachment to the stake, it being understood that the upper end of the rope is permanently attached to the tent at 1^a. 95

The loop is then adjusted as to its length, by turning the block to dotted position in Fig. 2 with the opening 8 parallel with the rope, so that the block will slide freely on the rope. After approximate adjustment is 100 made, the block is then turned to the position of full lines causing the length to be shortened a distance equal to the length of the bore or opening 8 and the rope, or that portion within the bore is frictionally clamped 105 within the walls of the bore or passageway 8.

At 9 and 10 these shoulders provide for an abrupt bend in the rope 3 and its loop 3', and the full length of rope is thus held, by the block or holder, in a symmetrical position 5 or straight line from the stake to the tent. The flaring recess 7 permits free manipulation of the block when taking up slack while the neck 5 affords a secure and firm hold for the knotted end of the rope, and similarly 10 the flaring mouths or longitudinally elongated openings of the bore 8 in the faces of the block permit ready manipulation of the block when taking up the slack.

It will thus be seen that by pulling up the 15 left end of the block in Fig. 2 the distance b between the dotted lines, the rope 3 is pulled down the distance a between dotted lines in Fig. 2, and then, when the block is freed to position in full lines, the horizontally dis-

posed portion of the rope in the bore 8 is 20 withdrawn from the length thereof to shorten the rope and take up slack.

Having thus fully described my invention, what I claim is:—

In a rope holder, a block adapted to be arranged normally oblique to the length of a rope, said block having a conical recess extending therethrough perpendicular to its longitudinal axis to receive the knotted end of a rope, and an obliquely disposed rope 25 30 35 passage through said block forming elongated openings to accommodate said rope and having opposed abrupt shoulders to the elongated openings of said passage on opposite faces of the block.

In testimony whereof I affix my signature.

THEODORE THORSON.
